UNITED STATES PATENT OFFICE.

JOHANES ANDERSON, OF HATTON, NORTH DAKOTA.

RAIL-FASTENER.

No. 890,396.

Specification of Letters Patent.

Patented June 9, 1908.

Application filed May 14, 1907. Serial No. 373,526.

To all whom it may concern:

Be it known that I, JOHANES ANDERSON, a citizen of the United States, residing at Hatton, in the county of Traill, State of North Dakota, have invented certain new and useful Improvements in Rail-Fasteners; and I do hereby declare the following to be a full, clear, and exact description of the invention, such as will enable others skilled in the art to 10 which it appertains to make and use the same.

This invention relates to new and useful improvements in fasteners for track rails and it has for its object to provide a device of 15 this character embodying a novel construction, combination and arrangement of parts.

The details of construction will appear in the course of the following description, in which reference is had to the accompanying 20 drawings forming a part of this specification, like characters of reference designating similar parts, throughout the several views, wherein:

Figure 1 is a top plan view illustrating the 25 manner of use of a rail fastener constructed in accordance with the present invention, the same being shown as applied to a railroad tie and a single track rail. Fig. 2 is a side elevation thereof. Fig. 3 is a central longitudinal section of said fastener. Fig. 4 is a 30 transverse section on the line 4—4 of Fig. 1.

Referring specifically to the accompanying drawings, the letter A, designates a rail tie and the letter B, the rails, in connection 35 with which the present invention is employed. The invention specifically comprises a base block 1, provided with openings 2, through which spikes 3 are passed to secure the base block to the tie. The block 1 is formed at 40 one side thereof with a raised lug 4, having an overhanging lip 5, and at a point opposite to said lip with an opening 6, which, adjacent the underneath face of the tie, is extended inwardly as at 7. The opening 6 is 45 of sufficient width to accommodate a rail clamp 8 and an adjusting key 9. The clamp 8 is constructed with an inwardly projecting lip 10 having a bevel underneath face 11 for engagement with one flange of the rail B, the 50 other flange of which is engaged by the lip 5 which in general conformation is similar to

the lip 10. The clamp 8 at its lower end is constructed with an extension 12 formed to fit into the recess extension 7.

The outer face of the clamp 8, designated 55 by the numeral 13, is preferably constructed with a wedge incline so that when the key 9 is inserted in the recess 6, it will force the clamp 8 into tight engagement with the rail in the manner described. The said key is 60 constructed with a head 9' and with shoulders 14 at each side of said head.

At one side of the bed 1 is a casing 15 in which is mounted a slideable latch member 16, the latter being forced inwardly by a spring 65 17, and having one end projected through an opening 18 in the end of the casing 15, the projecting end affording means whereby the latch member 16 may be manually displaced.

In use, the parts are assembled as de- 70 scribed and the latch member 16 has its working portion engaged with the shoulder 14 of one side of the head 9', thereby preventing accidental displacement of the key 9 from the opening 6 in the assembled relation 75 of parts.

Should it be desired for any reason to remove the rail sections B for substitution or repairs, the latches 16 are manually displaced and the keys 9 successively drawn from the 80 openings 6 throughout the length of the rails.

The rail fastener embodied in the present invention is simple in construction, inexpensive to manufacture and practical and efficient in use.

85 From the foregoing description it will be seen that simple and efficient means are provided for accomplishing the objects of the invention, but while the elements herein shown and described are well adapted to serve the 90 function set forth, it is obvious that various minor changes may be made in the proportions, shape and arrangement of the several parts, without departing from the spirit and scope of the invention as defined in the ap- 95 pended claims.

What is claimed is:

A rail fastener of the type set forth comprising a bed block constructed with an overhanging lip, with an opening at a point oppo- 100 site to said lip, said opening having an inward extension communicating with the

lower face of said bed block, a clamp disposed in said opening and having an inwardly pointing lip confronting said last named lip and an extension formed to engage in the extension 5 of said opening, a key disposed in said opening bearing against the outer face of said clamp, said key being constructed with a shoulder at one side thereof, and a displace-

able spring pressed latch member for engagement with said shoulder. 10

In testimony whereof, I affix my signature, in presence of two witnesses.

JOE ANDERSON.
